UNITED STATES PATENT OFFICE.

AXEL JOHNSON, OF OAKLAND, CALIFORNIA.

PORTABLE ELECTRIC RADIATOR.

Application filed June 1, 1926. Serial No. 112,836.

This invention relates to electric heaters and more particularly to heaters of the portable type resembling the conventional radiator, and to a heater wherein reflection and air circulation are employed to obtain maximum efficiency in the apparatus.

Among the objects of the invention is the construction of a heater from unit sections, which may be varied in number depending 10 on the size of the heater to be manufactured, and to form these structural units in such manner that they may be assembled with the minimum of labor and manufactured at a minimum cost. To construct a heater of the 15 multiple duplicate unit type wherein the units are of simple, cheap and effective formation, and when assembled provide an efficient electric heater of rich appearance, which may be moved about the place to be heated, and the current for supplying the heating elements thereof may be obtained from fixed sockets to which is connected a flexible conductor.

With the above mentioned and other objects in view, the invention consists in the novel construction and combination of parts hereinafter described, illustrated in the accompanying drawings and pointed out in the claims hereto appended; it being understood 30 that various changes in the form, proportion, size and minor details of construction within the scope of the claims may be resorted to without departing from the spirit or sacrificing any of the advantages of the invention.

To more fully comprehend the invention, reference is directed to the accompanying drawings forming a part of the application and wherein—

Fig. 1 is a view in elevation of the preferred embodiment of my invention, as viewed from the rear of the heater, with a portion of the rear wall broken away exposing the interior of the heater structure.

Fig. 2 is a view in broken top plan.

Fig. 3 is a view in vertical section.

Fig. 4 is a view in end elevation.

Referring more particularly to the several views of the drawings, wherein like characters of reference designate corresponding parts—1 indicates a pair of radiator end plates provided with supporting legs 2, and preferably formed of cast material. The end plates 1 are united at their top by tie rods 3 and adjacent their bottom by a bottom plate, 4 the latter being secured to the end plates by attaching devices passing through

lug 4' extending inwardly from the inner faces of said plates. Between the end plates are held the heater front and rear walls 5 and 6, the same being preferably constructed of sheet material and provided with vertically disposed flutes 7. Both front and rear walls 5 and 6 are constructed of a plurality of vertically disposed units 8, the same being formed on their vertical edges with flanges 9, which abut on the assembling of the units.

The flanges are formed with apertures near their upper ends, through which extend the tie rods 3, and between opposing flanges 70 of the respective units there is interposed a tubular spacing member 10 through which the tie rods pass. The lower ends of the units forming the respective walls are held together by other tie rods 11, also extending through apertures in the flanges of the units, and between the flanges of the respective units are interposed tubular spacers 12 surrounding the rods 11.

The lower edges of the front and rear 80 walls 5 and 6 extend to a point opposite the longitudinal side edges of the bottom plate 4, and their upper ends terminate substantially flush with the upper ends of the respective end plates 13, which in turn extend above and are united to the inner faces of the end walls 1. The front wall 5 is provided with a vertical series of perforations 14 to admit of the reflection of the glow of the heating element, hereinafter described, and the passage of heated air from the interior of the heater therethrough.

Resting on the upper ends of the front and rear walls 5 and 6 and the end plates 13 is a top wall 15 preferably of grill formation, and constructed in transverse sections, each formed on its transverse edge with a depending flange 16, the flanges of adjacent sections when assembled abutting, as in Fig. 1, and formed with apertures 17 through 95 which extend the tie rods 3. The end sections of the cover plate 15 are illustrated as being provided with handles 18, but this is understood to be optional.

Arranged in parallel spaced relation to 105 the inner face of the rear wall 6 and adjacent thereto is a reflector wall 19, the upper portion of which curves forwardly at 20 toward the upper end of the front wall 5 and lies beneath the undersurface of the top 110 plate 15. This forward curved extension of the reflector 19 is secured by suitable means

to depending lugs 21, preferably integral with the sections of the top wall 15.

The space between the rear wall 6 and reflector wall 19, indicated by the numeral 22, forms an air circulating passage 1 at the rear of the heater, the upper end of which terminates beneath the top wall 15.

Disposed in vertical parallel spaced relation within the heater are suitable supporting cores 23 having wound therearound resistance elements 24, the elements and their respective cores constituting heating units which are interconnected by buss bars 25.

Disposed transversely across the upper and lower ends of the respective units are mounting bars 25, the ends of which cooperate with the flanges 26 extending inwardly from the end plates 1, and said bars are secured at their corresponding ends to the respective flanges by tie bolts 27 extending therethrough.

It will thus be apparent that the elements may be removed from the heater as a unit.

Current is supplied to the elements through leads 28 which are adapted for connection with the main supply leads 29 through a switch 30 mounted on one of the end plates, the lead 29 passing through an insulated aperture 31 within said end wall, as illustrated in Fig. 1.

When in use, the glow of the resistance elements 24 will be reflected by the plate 19 through the ports 14 in the front wall; the air entering the lower part of the heating chamber within which the units are mounted will be caused to rise therein, become heated by contact with the units and pass from the chamber through the apertures 14. The air entering the lower portion of the passage 22 will be heated by conduction and rise from the heater through the grill top wall 15. The provision of the air circulating passage 22 insures that the rear wall of the heater will be maintained cooled at all times.

I claim:

1. A portable electric radiator comprising end, back and ported front and top walls forming a chamber having an open front, top and bottom, a pair of tie rods uniting the upper ends of the end walls, one rod of the pair uniting the back wall with one edge

of the top wall and the other rod of the pair uniting the front wall with the other edge of the top wall, a reflector wall disposed vertically within the chamber dividing the same longitudinally into a heating unit compartment and an air passage, said wall overlying the heating unit compartment beneath the top wall, and electric heating elements within the heating chamber.

2. A portable electric radiator comprising end, back and ported front and top wall members, forming a chamber having an open front, top and bottom, the respective walls each being formed of a plurality of substantially duplicate units, a reflector wall vertically disposed within the chamber and dividing the same longitudinally into a heating unit compartment in rear of the front wall and an air passage between the reflector wall and the back wall, the upper end of said reflector wall overlying the heating unit compartment beneath the top wall, a pair of tie rods uniting the end walls and one of the rods of the pair uniting the back wall forming sections with the top wall forming sections, and the other rod of the pair uniting the front wall forming sections with the top wall forming sections, and heating elements within the heating unit compartment.

3. A portable electric radiator comprising end, front, back and top wall members, the respective walls each being formed of a plurality of substantially duplicate units and providing a heating chamber, the front and top walls being further provided with apertures, a reflector wall within the chamber and formed of a plurality of substantially duplicate units, said reflector facing the ported front wall and forming with the back wall a vertically disposed air passage extending the full length of the chamber from top to bottom, a plurality of electric heating elements disposed within the chamber in advance of the reflector, and tie rods uniting the upper ends of the end walls with the top wall, one of said rods each passing through the respective front and back walls.

In testimony whereof I have signed my name to this specification.

AXEL JOHNSON.
